UNITED STATES PATENT OFFICE.

HYMAN SELTZER, OF NEW YORK, N. Y.

SWIMMING DEVICE.

1,171,752.

Specification of Letters Patent. Patented Feb. 15, 1916.

Application filed October 30, 1914. Serial No. 869,419.

To all whom it may concern:

Be it known that I, HYMAN SELTZER, a subject of the Czar of Russia, and a resident of New York, borough of Brooklyn, county 5 of Kings, and State of New York, have invented a certain new and useful Improvement in Swimming Devices, of which the following is a full, clear, and exact specification.

10 This invention relates to a class of devices adapted to be used in aquatic sports.

My invention has for its object primarily to provide a swimming device designed to be employed by a person for floating at various depths in water while in an upright position to appear as if walking as well as permitting the person to be propelled when in other attitudes, thereby allowing feats which are usually considered impossible to be readily accomplished by one who is skilled in the manipulation of the device, and which consists essentially of a supporting frame adapted to be detachably fastened to a person so as to be disposed between the feet, and 20 to the frame is revolvably mounted a propeller adapted to be driven by the feet of the person when moved alternately in upwardly and downwardly directions.

Other objects of the invention are to provide operative means on the frame for driving the propeller; to provide crank members whereby the operative means may be operated by the feet of the person using the device; to provide a retainer for permitting the 35 frame to be suspended from the person; and to provide means for detachably fastening the retainer to the body of the person.

With these and other objects in view, the invention will be hereinafter more particularly described with reference to the accompanying drawings, which form a part of this specification, and will then be pointed out in the claims at the end of the description.

45 In the drawings Figure 1 is a fragmentary view showing a front elevation of one form of the swimming device embodying my invention as employed by a person. Fig. 2 is a fragmentary view showing a side elevation of the device and the manner of applying it to a person. Fig. 3 is an enlarged detail side view, partly broken away, of the device. Fig. 4 is an enlarged detail front view, partly broken away, of the device, and 55 Fig. 5 is a view, taken on the line V—V of Fig. 4.

The swimming device has a supporting frame 10 composed preferably of a bar 11, and on one end of the bar is formed an elongated head 12 in the free end of which 60 is a recess 13 disposed lengthwise of the head. Extending laterally from the free end portion of the head 12 is one end of a curved bracket, as 14, provided with a sleeve or ring 15 on its other end, and this ring is in 65 alignment with the head 12 in spaced relation to its free end so that the opening through the ring is in register with the recess of the head.

In the recess 13 of the head 12 of the supporting frame is rotatably disposed one end of a shaft 16 which is of sufficient length to extend some distance beyond the head, and on the end of the extending part of the shaft is a propeller 17. The propeller may 70 be of any well known or preferred type adapted when driven to cause a person, as 18, who may be using the device to float at suitable depths below the surface of water as well as being adapted to propel the person 75 while in the water.

As shown in the drawing the device when in use is disposed between the legs of the operator so that the propeller 17 will be underneath the operator for being driven by 80 the feet, and serving as means to permit the propeller and its shaft to be operated, on the shaft 16 is a bevel gear 19 having a sleeve 20 extending from one of its ends.

The gear 19 and its sleeve is arranged on the 85 shaft of the propeller so as to be disposed between the ring 15 of the bracket 14 and the opposed end of the head of the supporting frame 10, and this gear is tightly held to the shaft of the propeller by a set screw 90 or the like passing through a threaded opening in the sleeve of the gear so as to engage the shaft of the propeller. The bevel gear 19 is in mesh with the teeth of a bevel-faced

drive gear, as 21, which is held on a shaft 100 22 journaled in the central part of the bar 11 of the frame of the device. To permit these parts to be operated by the feet of the person using the device whereby the propeller may be driven, on one end of the shaft 105 22 of the drive gear 21 adjacent to this gear is held one end of a crank member 23, and on the other end of this shaft is held one end of a second crank member 24. The crank members 23 and 24 are disposed in opposite directions relatively to each other, and these crank members preferably extend outwardly 110

of the frame 10 on an incline so that the free ends thereof will be suitably spaced from the frame and from the drive gear 21. On the opposite end of the crank member 23 is 5 pivoted a pedal 25 provided with a cross-strap 26, and on the opposite end of the crank member 24 is pivoted a pedal 27 also having a similar cross-strap 28, these straps serving to hold the feet of the person operating the device against accidental displacement on the pedals.

For the purpose of permitting the frame 10 to be suspended to the operator of the device, I provide a retainer, as 29. The retainer 29 is preferably of a form having a front rod 30, two spaced back rods 31 and 32, and a brace, or reinforcing bracket 33, all of which is preferably made of stiff wire so as to be light in weight as well as serving 10 to rigidly hold the device proper when in use. The front rod 30 and the back rod 31 may be integrally formed by bending the central part of a single strip of wire to provide a loop, as 34, which is rotatably disposed over one end of a pin, or lug 34 extending in a lateral direction through an opening in the central part of the bar 11 of the frame 10, and these rods diverge outwardly with respect to the pin 34. The upper ends 15 of the rods 30 and 31 terminate with hooks as 35 and 36, and both of the rods are of sufficient lengths to extend above the frame 10 a distance whereby the hooks thereof may be detachably fastened to the waist of the 20 operator of the device. The back rod 32 is similar in length to the back rod 31 as well as being correspondingly disposed to the back rod so as to be spaced therefrom, and the upper end of the back rod 32 also terminates with a hook 37. The back rod 32 and the brace 33 may also be integrally formed of a single strip of wire, the central part of which is bent to form a loop, as 38, which is 25 rotatably disposed over the other end of the pin 34 of the bar 11 of the frame of the device. The wire is then guided upwardly and bent tightly around the front rod 30 at a part thereof which is on alignment with the upper end of the bar 11 of the frame, and 30 this wire is disposed crosswise toward the center of both of the back rods 31 and 32. Midway of the distance between the front rod and the back rods the wire is curved outwardly in the form of approximately the 35 quadrant of a circle, and the wire is directed toward and tightly bent around the back rod 31 after which the wire is reversely twisted around part of itself including the curved part. A substantially U-shaped recess or 40 holding part, as 39, is then provided in the brace 33 for removably receiving the upper end of the bar 11 of the frame 10 by curving the wire in substantially the quadrant of a circle in an opposite direction to the other 45 curved part thereof, and the wire is directed

crosswise to the back rod 32 around which it is tightly bent. The wire is afterward re-twisted over itself throughout its length, and this wire terminates with a depending loop, as 40, at the juncture of the brace with the front rod 30. In this manner, as shown, the brace 33 serves to strengthen the rods 30, 31, 32 as well as holding the rods in spaced triangular arrangement.

Serving as means to permit the device to be detachably applied to a person I provide a belt, as at 41, having a longitudinally disposed strap 42 through both end portions of which are a number of eyelets 43 and 44. Depending from spaced parts of the strap 42 intermediate its ends are two back straps 45 and 46, and on the free ends of these straps are buckles 47 and 48 of well known forms, as shown, which are adapted to be engaged in the usual way by the eyeleted ends of the strap 42. At the juncture of the strap 42 with the strap 45 is a gusset 49, and a similar gusset 50 is provided at the juncture of the strap 42 with the strap 46. Between the lower ends of the straps 45 and 46 is a third gusset 51, and extending from each of these gussets is an eye, at 52.

While I have shown and described a specific form of the supporting belt 41 for permitting the device to be detachably applied to a person, I do not claim this particular belt as part of my present invention as any suitable type of belt or other means may be used instead thereof.

In order to apply the device to a person for use the strap 42 of the belt 41 is guided around the waist while the straps 45 and 46 are disposed under the legs of the person. The ends of the waist strap are then fastened to the buckles of the leg straps in the manner shown in Figs. 1 and 2. The hooks of the back rods 31 and 32 of the retainer 29 are then fastened to the eyes 52 of the gussets 49 and 50 of the belt, and the hook of the front rod 30 is fastened to the eye 52 of the gusset 51. The device proper will then be disposed between the legs of the person, as shown in Fig. 2, and when the person has passed into water the feet of the operator of the device are placed on the pedals of the crank members 23 and 24 so that the straps of the pedals will be guided over the feet and the upper end of the bar 11 of the frame 10 is disposed in the recess 39 of the retainer 29. The propeller of the device will thereby be disposed below the operator's feet, and to further hold the device in this position to the bracket 14 of the head 12 of the frame is secured one end of a spring rod 55 which extends upwardly, and the upper end of this rod terminates with a hook 56 which is removably guided into the depending loop 40 of the brace 33. The propeller 17, its shaft 16, gear 19, drive gear 21, and the shaft 22 are then driven by rotatably

moving the pedals and crank members 23 and 24 by the feet of the operator similar to driving a bicycle. When in an upright position in the water the operator of the device 5 may be raised or lowered to different depths by driving the propeller at various speeds, and when the operator assumes different attitudes in the water for instance by lying forwardly or backwardly and then 10 operating the device in like manner the person will be propelled at a suitable speed.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to 20 make such changes as fairly fall within the scope of the appended claims.

Having thus described my invention, I claim as new and desire to secure by Letters Patent:—

25 1. A swimming device comprising a frame bar, a propeller journaled in the frame bar, foot operated means for driving the propeller, and a retainer attached to the frame

bar to permit relative movement of the frame bar and retainer and means for holding the frame bar in fixed position to the retainer, when the device is in use. 30

2. A swimming device comprising a supporting frame in the form of a bar adapted to be straddled by a person, propeller-carrying shaft journaled in the lower end of the bar against longitudinal displacement, pedal-operated geared means for rotating the propeller shaft by the feet, a retainer pivoted to the bar intermediate its 35 ends and comprising a front rod and a pair of back rods, means limiting the movement of the bar in the direction of the retainer, means carried by the frame and retainer for cooperation in holding the parts in the last 40 mentioned position with the propeller beneath the feet of the operator, and a body engaging member provided with means for connecting the retainer thereto. 45

This specification signed and witnessed 50 this twenty-ninth day of October A. D. 1914.
